Attorney

WITNESS:

UNITED STATES PATENT OFFICE.

ISAAC HARRIS, OF DETROIT, MICHIGAN.

SPARK PLUG.

Application filed March 14, 1924. Serial No. 699,268.

This invention relates to improvements in spark plugs and has for an object the provision of means to indicate whether or not the plug is properly firing. 5
 5 Another object of the invention is the provision of means for intensifying the spark within the engine cylinder and for preventing accumulation of oil at the firing points, so that the points will not carbonize 10 and so that proper operation of the plug will be assured. 10

With the above and other objects in view, the invention further includes the following novel features and details of construction, 15 to be hereinafter more fully described, illustrated in the accompanying drawings and pointed out in the appended claim.

In the drawings:—

Figure 1 is a sectional view of a spark 20 plug constructed in accordance with the invention.

Figure 2 is a bottom plan view of the same.

Figure 3 is a sectional view on the line 25 3—3 of Figure 1.

Referring to the drawings in detail where-in like characters of reference denote corresponding parts, the reference character 10 indicates the shell of the plug which is exteriorly threaded as shown at 11 for removable engagement with an engine in the usual manner. Located within the shell is a core 12 which is held therein by means of a nut or gland 13, while suitable packing 14 is 35 provided to prevent escape of compression through the plug.

The core 12 is of novel construction and includes an enlarged portion 15 which is hollow so as to provide a chamber 16, the latter being provided with openings 17 and 18.

The core 12 carries a sectional power electrode which includes sections 19 and 20. The last mentioned section is threaded at 45 one end and passes through the opening 18 and the wall of the latter is provided with an annular groove 21 which is adapted to receive a retaining element 22 which serves to connect the section 20 of the electrode to the core. This retaining element may be 50 of any suitable material such as soft or

moulten metal which is placed within the opening around the electrode section 20 so as to engage the threads and the groove 21 and after this metal becomes hardened the 55 electrode section will be securely held in place without any auxiliary fastening means such as screws, nuts or the like. The electrode section extends beyond the top of the core and is provided with a nut 23 for the 60 retention of the usual lead wire.

The section 19 of the power electrode extends within the chamber 16 and is provided with a coil 24 which surrounds and is spaced from the adjacent end of the section 20 of the electrode. This provides a spark gap or spark intensifier. It is preferred to form the core 12 and the chamber 16 of tough glass which will withstand a high temperature so that the walls of the chamber will 70 be transparent in order that it may be seen whether or not the plug is functioning. The upper part of the chamber 16 forms a vacuum dome and as the opening 17 is of a restricted character and atmospheric pressure is the same upon opposite sides of the opening, the passage of water, gas fumes and so forth through the opening will be 75 prevented.

The lower end of the shell 10 has extending therefrom a ground electrode 25 which is provided with an upwardly and inwardly extending arm 26 and a substantially circular terminal 27 which receives and surrounds the adjacent end of the section 19 of the power electrode. Oil pumped into an engine cylinder and reaching the electrodes will therefore gravitate down and drop from the arm 26, while the intensified spark at this end of the plug will keep the electrodes free from carbon and in proper firing condition. 80

The invention is susceptible of various changes in its form, proportions and minor details of construction and the right is here-in reserved to make such changes as properly fall within the scope of the appended claim. 85

Having described the invention what is claimed is:—

A spark plug comprising a shell; an insulating core within the shell, said core being provided at one end with an enlarged 100

head having a chamber therein, a sectional power electrode having one member thereof extending longitudinally through said insulating core and having a spiral formed at 5 one end thereof, and located within said chamber, the other member being supported in alignment therewith and having a portion

thereof extending concentrically with the spiral portion, a ground electrode secured to said shell and having a loop portion surrounding said power electrode. 10

In testimony whereof I affix my signature:

ISAAC HARRIS.
